(57) **CLAIM**

The ornamental design for work clothing, as shown and described.

DESCRIPTION

4.1-4.2 Work clothing

4.1 shows a front elevational view of our new design for work clothing, with the garment lying flat; and

4.2 shows a rear elevational view thereof.

The term "BRAGARD" forming part of the claimed design is a registered trademark of Bragard SAS, France.

The broken lines in the drawings depict stitching or seams and form no part of the claim.
